CLAIM

The ornamental design for a loudspeaker, as shown and described.

DESCRIPTION

FIG. 1 is a top perspective view of a loudspeaker, showing our new design;

FIG. 2 is a side elevational view thereof, shown in enlarged scale;

FIG. 3 is another top perspective view thereof;

FIG. 4 is a partially enlarged view thereof, taken from FIG. 3;

FIG. 5 is a bottom perspective view thereof;

FIG. 6 is a partially enlarged view thereof, taken from FIG. 5;

FIG. 7 is a front perspective view thereof;

FIG. 8 is a rear perspective view thereof;

FIG. 9 is a partially enlarged view thereof, taken from FIG. 7; and,

FIG. 10 is a partially enlarged view thereof, taken from FIG. 8.

The broken lines in the figures illustrate the portions of the design that form no part of the claimed design.

The dot-dash broken lines are included to show partially enlarged views only and form no part of the claimed design.

1 Claim, 9 Drawing Sheets
